CLAIM

The ornamental design for a set of jump rope handles, as shown and described.

DESCRIPTION

FIG. 1 is a perspective view of a set of jump rope handles showing my new design, showing only one of the handles for convenience of illustration;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view of a pair of jump rope handles thereof; and,

FIG. 9 is another perspective view of a pair of jump rope handles thereof.

The broken lines shown in FIGS. 8 and 9 are for the purpose of illustrating environmental structure, which form no part of the claimed design.
